(57) **CLAIM**

The ornamental design for a combined disc player, clock and
radio receiver, as shown.

DESCRIPTION

FIG. 1 is a perspective view of a combined disc player, clock
and radio receiver showing our new design;

FIG. 2 is a perspective view thereof, wherein a dock tray
shown in broken lines is in the open position; and,

FIG. 3 is a front elevational view thereof.

The even broken line showings in the figures are for illustrative
purpose only and form no part of the claimed design. The
dot-dash broken lines therein define, but are not included in,
the boundaries of the claimed design.
